UNITED STATES PATENT OFFICE.

EUGEN SECKLER, OF PATERSON, NEW JERSEY.

COMPASS-BOARD.

1,118,309.

Specification of Letters Patent.

Patented Nov. 24, 1914.

Application filed January 13, 1914. Serial No. 811,791.

To all whom it may concern:

Be it known that I, EUGEN SECKLER, a subject of the Emperor of Germany, residing at Paterson, in the county of Passaic 5 and State of New Jersey, have invented certain new and useful Improvements in Compass-Boards, of which the following is a specification.

This invention relates to looms and it 10 consists in certain improvements in devices employed therein, known as "comber" or "compass" boards, for confining the harness cords in more or less compact disposition, such improvements contemplating a 15 substitute for the usual perforated board or plate serving as the comber or compass board, which has the objection that it neither allows its ready removal from the group of harness cords when its holes become worn 20 thereby, or any change in the spacing of the harness cords, and is, moreover, peculiarly susceptible to becoming cut by the cords, since usually it is formed of wood.

Referring, now, to the accompanying 25 drawing, Figure 1 shows in side elevation a jacquard machine and a frame in which the improved comber board structure is supported; Fig. 2 is a plan view of a fragment of the aforesaid frame and one of the 30 proved comber boards, a part of which is shown in section; Fig. 3 is a transverse sectional view of Fig. 2; Fig. 4 is a view showing in front elevation several of the comber boards like that shown in Fig. 2 supported 35 in the frame, only one side of which is shown, portions of the comber boards appearing in section; Fig. 5 is a plan view of a modification of my invention; Fig. 6 is an enlarged sectional view on substantially the 40 line $\alpha-\alpha$ in Fig. 5; Fig. 7 is a sectional detail of the right hand end of what is shown in Fig. 5; and, Fig. 8 is a perspective view of one of the sliding rod-groups appearing in Fig. 5.

45 Referring, first, to Figs. 1 to 4, from the hooks a of a jacquard b depend the harness cords c , which extend between two rails d forming a frame in which to support the improved comber board structure, being rabbed at e on their inner sides for that purpose (see Figs. 2 and 3). f is a rectangular frame which rests in the rabbets e and may be overlapped by the strips g suitably secured upon the rails d , the frame f being 50 removable from the frame constituted by the rails d either by removing one of the

strips g or by sliding the frame f longitudinally of the rails until it clears them. The sides or members f^3, f^4 , which directly slide in the rails or members d , are perforated horizontally with equal numbers of 60 opposed holes and in these are loosely arranged the parallel rods or wires h ; the sides f' and f^2 are provided with similar holes, opposite to each other and equal in 65 number, in which are arranged the ends of the wires or rods i . Since the two groups of wires and rods h and i cross each other, holes are formed through which the harness 70 cords c are extended. The rods i are held 75 from endwise displacement out of the frame f by the strips j , secured removably to the outer surfaces of the sides f', f^2 of the frame f by means of screws k ; the rails d may serve to prevent similar displacement of 80 the rods h .

In order to make it possible to change the spacing of the harness cords, or to remove one of the compass boards and substitute another, I form a section of the frame f , 85 as for instance the side f^2 , removable, said side being shown in Fig. 2 as held in place by the screws l . Upon removing the side f^2 (or either strip j) the rods i may be removed or such other changes made with respect thereto as will alter the spacing of the harness cords transversely in Fig. 2; upon removing one of the strips g and elevating one end of the frame f similar changes can be made with respect to the rods h ; finally, 90 it will readily be seen that by removing the side f^2 of the frame and the several rods the comber board structure may be removed bodily from the group of harness cords, having first established the comber board 95 which is to take its place in proper relation to the harness cords, so that the re-threading incident to the old style of comber board is avoided.

In Fig. 4 several of the comber board 100 structures are shown as supported in the frame afforded by the rails d . They may be arranged close together or more or less spaced from each other, as circumstances require. 105

Referring now to Figs. 5 to 8 m is a rectangular frame comprising two long sides m' and two short sides m^2 . The two long sides have opposite longitudinal grooves n , and the top surfaces of the two 110 short sides m^2 are somewhat lower than these grooves. In cross-bars o , inset in the

upper inner edges of the short sides m^2 , are fitted the ends of the longitudinal rods or wires p , the holes in the cross-bars receiving the ends of the rods extending only partway 5 through the cross-bars so that the rods are confined against endwise displacement. q designates several cross strips penetrated by the several rods p and maintaining them properly spaced from each other. Over the 10 rod-group p above described are arranged one or more other rod-groups slidable in the grooves m . These include the end members or shoes r received in the grooves n and the parallel rods s loosely penetrating said end-members so as to be removable therefrom 15 when the latter are removed from the grooves. The rods s may be kept properly spaced by the cross-strips t which they penetrate. On a view to Fig. 5 it will be seen 20 that the rods p and s , by crossing each other, afford the guiding holes for the harness cords.

In order to facilitate clearing the harness cords from the rod-groups s , one of the sides, 25 m' , of the frame m may include a removable strip u to afford one side of the slot n in such side, and when the strip u is removed any rod-group may be elevated for effecting the necessary change in the disposition of 30 the rods s therein. Ordinarily, in the adaptation in which the modification shown in Figs. 5 to 8 is designed to be employed, it will be unnecessary to clear the harness cords from the rods p , but should it be 35 necessary, it may be accomplished by detaching one of the cross-bars o , which are removably held in place by screws as shown in Fig. 5.

Copies of this patent may be obtained for five cents each, by addressing the "Commissioner of Patents, Washington, D. C."

Having thus fully described my invention, what I claim as new and desire to secure by 40 Letters Patent is:—

1. A comber board structure including two crossed groups of parallel spaced rods together forming the guiding holes for the harness cords and a support for said rods 45 including sliding members having penetrating holes receiving the opposite ends of one group of said rods and parallel members affording guides for the first-named members and obstructing endwise movement of 50 said group of rods.

2. A comber board structure including two crossed groups of parallel spaced rods together forming the guiding holes for the harness cords and a support for said rods 55 receiving the ends thereof and confining each rod against longitudinal displacement, said support including parallel guiding members and shoes slidable on said members and supporting the ends of one group 60 of the rods, substantially as described.

3. A comber board structure including a frame, a group of parallel spaced rods supported therein at their ends, a sliding structure carried by said frame and including 65 other parallel spaced rods crossing the first rods and forming therewith the guiding holes for the harness cords, substantially as described.

In testimony whereof I affix my signaure 70 in presence of two witnesses.

EUGEN SECKLER.
